UNITED STATES PATENT OFFICE.

THOMAS H. STACKHOUSE, OF PHILADELPHIA, PENNSYLVANIA.

MACHINE FOR PRINTING FROM STENCILS.

SPECIFICATION forming part of Letters Patent No. 513,212, dated January 23, 1891.

Application filed January 14, 1893. Serial No. 458,352. (No model.)

To all whom it may concern:

Be it known that I, THOMAS H. STACKHOUSE, a citizen of the United States, and a resident of the city and county of Philadelphia and State of Pennsylvania, have invented certain new and useful Improvements in Machines for Printing from Stencils, of which the following is a specification.

My invention relates to improvements in machines for printing from stencils, and more particularly to improvements in reciprocating machines for printing from stencils formed upon prepared sheets of paper either by perforation or abrasion, and the object of my invention is to furnish a machine of this character which will be simple and inexpensive in construction, which may be operated more rapidly than machines heretofore constructed for this purpose and with less wear and danger of accident to the stencil.

My stenciling machine consists of a stationary bed plate upon which is mounted an open carriage which carries the frame which carries the stencil. An inking roller is mounted upon arms pivoted to the bed plate and is adapted to ink the top of the stencil, and a rolling platen carried upon suitable bearings is adapted to press the paper to be printed up against the bottom of the stencil. This platen is placed preferably directly beneath the inking roller, and the inking roller and platen are so arranged as to bear, the former against the stencil, and the latter against the paper to receive the impression from the stencil. Upon the shaft of the platen are gear wheels, and upon the carriage which carries the stencil are racks gearing into and driving these gear wheels and the platen. Upon the shaft of the inking roll are gear wheels gearing into and driven by the gear wheels on shaft of platen. These gears are so proportioned as to drive the inking roll and platen at exactly the same speed as the carriage and stencil. Hence the stencil is never subjected to any torsional or other strains which might impair its usefulness and shorten its life.

My invention consists further in devices for separating the inking roll and platen when the carriage is upon its backward stroke, in devices for holding and guiding the paper on its way to be printed, and for receiving it

after having been printed, and in other details hereinafter fully described.

In the accompanying drawings forming part of this specification, and in which similar letters of reference indicate similar parts throughout the several views, Figure 1, is a top view or plan of my printing machine; Fig. 2, a side elevation of Fig. 1; Fig. 3, a horizontal sectional elevation of Fig. 1 on line 1—2; Fig. 4, a transverse sectional elevation of Fig. 1 on line 3—4; Fig. 5, a plan of front part of paper feeding table, and Fig. 6, a side elevation of the central part of my machine, showing the inking roll and its connected parts thrown upward; Fig. 7, a front view of the adjustable pieces V, W, carried on the forward ends of the arms I, L.

A is the stationary bed plate of my machine which is preferably constructed of metal.

B is a carriage mounted and adapted to slide upon the bed plate.

In the drawings I have shown the carriage mounted and sliding upon rails C, Figs. 1, 3 and 4, which are upon the inner part of the sides of the bed plate and which may be cast with the bed plate, or formed separately and bolted to it.

C² are clamps or guides which are secured to the lower part of the carriage and which pass around and under the rails C, as shown in Fig. 4, and prevent the carriage from being lifted from the rails.

D, is a stencil holding frame. This frame is constructed of two pieces; the lower piece *a* being somewhat narrower than the upper piece and its upper face being furnished with a groove *b*, as shown in Figs. 3 and 4, and its upper part *c* being furnished upon its lower face with a tongue *d* adapted to enter the groove *b* in the lower part. The upper part *c* of the frame is L shaped as shown and is secured to the lower part by means of hooks *e*, or in any other substantial manner. The stencil is clamped and stretched between the bottom and top parts of the frame, the peculiar shape of which holds it firmly.

While I prefer to use a frame constructed as shown it will be understood that any of the well known forms of frames for stretching and holding stencils may be used.

My device for holding the stencil frame to the carriage consists of two or more J shaped springs E, Figs. 1 and 3, which are carried by the forward end and preferably at opposite sides of the carriage. These springs or pieces of metal bear against the forward end and top of the frame and clamp this part of the frame securely to the carriage. The frame is prevented from moving sidewise by flanges F projecting upward from the carriage and against which the sides of the frame bear. The rear of the frame is held down against the carriage by means of clamps G which are carried by the carriage and which are furnished with oblong heads which may be turned sidewise so as to release this end of the frame when it may be desired to remove the frame from the carriage. The inking roll H is carried upon arms I pivoted to the sides of the bed plate at J. Directly beneath the inking roll is a platen K, the shaft of which is carried upon arms L which are pivoted to the sides of the bed plate preferably at J. The arms L, and the platen are supported by means of springs M, the upper ends of which bear against the lower part of the forward ends of the arms L and the lower ends of which may bear against a leg or bracket N extending from the bed plate. Upon the carriage B, and running lengthwise with this carriage, are racks O, one preferably upon each side of the carriage; these racks gear into and drive gear wheels P which are fast to the shaft of platen K.

R, are gear wheels fast to shaft of inking roll H and which during the forward stroke of the carriage and stencil are in gear with and driven by the gears P, but which during the return stroke of the carriage and stencil are lifted from the gears P. During the forward or printing stroke of the carriage and stencil the inking roll H bears upon the top of the stencil, and the platen K presses the paper to be printed firmly against the bottom of the stencil. The rack O drives gear wheel P and platen K at exactly the same speed. Consequently there is no strain upon the stencil while it is in action which would be liable to injure it. It will be noticed that the inking roll and platen, the latter of which is directly beneath the former, only engage the stencil along one line at one time. It will be obvious that the gear wheel R may be driven by a rack, similar to the rack O, instead of being driven by gear wheel P which is driven by the rack; or the rack O might have teeth upon its top similar to those upon its bottom which would drive gear R and inking roll H; or the rack O may be reversed and engage the gear R and the gear R would then engage the gear P. This latter construction would be preferable in certain classes of machines. During the backward stroke of the carriage the inking roll is lifted and the platen lowered so that both will be completely out of contact with the stencil.

My device for separating the rolls consists

of double faced cams S, one of which is placed on each side of the bed plate, and which travels upon guides T carried by suitable brackets U carried by the frame A. Upon the arms I—L which carry the ink roll and platen are adjustable pieces V—W which are adapted to bear against the faces of the cam S, and upon the carriage are adjustable tappets Y'—the former upon the front of the carriage, and the latter upon the rear. These tappets are adapted to engage the ends of the cam S and slide it forward or backward on the guide T. In the drawings the carriage is shown as at the forward end of its stroke, the tappets Y' have engaged and moved forward the cams S, the inclined faces of which have engaged and lifted the engaging pieces V—W, carried by arms I—L, and the ink roll and platen are moved away from the stencil. When the carriage is drawn back and just before it reaches the end of its stroke the tappets Y engage the forward end of cam S and move this cam back allowing the arms I—L to fall and the ink roller and platen to engage the stencil again. Ordinarily the weight of the ink roller and its connected parts will be sufficient to force the ink through the stencil, but should additional pressure be necessary, springs A' one end of which is attached to the bed plate at J² or to a stud or arm carried by the bed plate, and the other attached to one end of a screw B' which is held by the arms I, or by a projection C' from these arms, may be used to draw the ink roller more firmly against the stencil. It will be seen that by means of screws B' the tension of the springs A' may be regulated as desired.

A front view of the adjustable pieces V, W, is shown in Fig. 7.

The paper feeding table D' is placed within and at the rear of the frame forming the bed plate. This table is adjustable both vertically and horizontally and it should be so placed that a continuation of its top line will be tangent, or nearly tangent, to the upper part of the platen roll when this latter is lowered as shown in Fig. 3.

Various devices may be employed to make the table D' adjustable. I have shown the table furnished with lugs E' which project from its bottom and which are furnished with slots E². E³, are slots in the sides of the bed plate A, which are at right angles, or nearly so, to slots E² in lugs E'. E⁵ is a threaded nut or washer which screw E⁴ enters, and by means of which and the screw, the table may be securely attached to the bed plate. The slots in the bed plate and lugs permit a movement of the table for adjustment.

F', G' are adjustable paper guides carried by table D'. The guide F' is placed at the rear of the table and has a screw F² passing through it and through a slot F³ in the table A. A thumb nut F⁴ on screw F² draws the head of this screw up against the bottom of the table, and forces the guide F' against the top of the table and locks the guide at the de-

sired point on the table, the slot F³ permitting the guide and screw to be moved backward or forward as may be necessary for different lengths of paper. The guide G', has 5 a screw G² passing through it and through a slot G³, placed preferably at right angles to slot F³. A thumb nut G⁴ operates in conjunction with screw G², to lock the guide G' at any point on the slot G³. The guide G' is 10 set either in or out as may be necessary for sheets of paper of different widths.

H', Fig. 3, is a box which is placed in front of the platen K and which receives the printed sheets of paper as they pass from the machine. 15

I' is a handle attached to the rear part of the carriage and by means of which the carriage may be operated.

Attached to or forming part of the arms I 20 which carry the inking roll H, is a frame J' which is furnished with suitable bearings in which shafts are journaled which carry a train of ink evening and distributing rolls K', K², K³, K⁴. The lower rolls K², K⁴, are journaled 25 in fixed bearings in the frame J'. The upper rolls K', K³, may be journaled in fixed bearings in the sides of this frame, but I prefer to journal the ends of their shaft in separate pieces or bars of metal L', L' which are secured 30 in an adjustable manner to the frame J' so that the upper rollers may be tightly forced against the lower rolls K², K⁴ and the inking roll H, or may be lifted entirely clear of these rolls.

35 In the drawings I have shown the metal pieces L' L', which carry the upper rolls, furnished with threaded studs M' which pass through slots N' in the sides of the frame J'. Thumb nuts O', on threaded studs can be operated 40 to hold the bearing pieces L' so as to force the upper rolls against the lower, or to hold them entirely out of contact.

The rolls being made of a composition which becomes more or less soft and sticky in warm 45 weather, it is advisable to separate them when not in use.

I have shown in the drawings a train of four ink distributing rolls; it will be understood however that this number of rolls may be increased or diminished if desired.

50 In inking the roll H, the ink is first placed upon the outside roll K⁴, for instance, by dropping it upon this roll from the tubes in which the ink is usually sold, and the roll H being lifted from the stencil as shown in Fig. 3, is 55 revolved by means of a crank P', Figs. 1 and 4, which is attached to the shaft of this roll. The roll H, drives by friction the train of rolls K' K² K³ K⁴ and the ink which has been placed 60 upon roll K⁴, is rolled out and evenly distributed upon all parts of the rollers by the time that it reaches the inking roll, upon which it is placed in a perfectly even manner.

To remove the stencil frame from the carriage, this latter is drawn back to the end of 65 its stroke and the arms carrying the inking

roll and its connected parts are thrown back as shown in Fig. 6, in which position they are completely out of the way. The clamps G are now turned so as to release the rear end of 70 the stencil frame, which may then be withdrawn from the springs E which secure its forward end and lifted from the carriage.

I am aware that reciprocating machines for printing from stencils have before been used, 75 but all the machines of this kind that I am familiar with are furnished with a solid carriage which forms the platen and which works tangentially to and drives the inking roll by the friction of the stencil passing in contact 80 with the said roll. The strains put upon the stencil by devices of this kind are very severe and greatly shorten its life, while the printing done by them is apt to be more or less blurred and unsatisfactory. Having 85 these defects in view I have furnished a means as hereinbefore described for independently driving the inking roll, the roll and stencil being always driven at exactly the same speed. I have also done away with 90 the flat platen and have made my carriage with an open center, the paper to be printed being held up against the bottom of the stencil by a rolling platen which is moved by gearing at the same speed as the stencil, and 95 which carries the paper along with the stencil, and discharges it at the front of the machine without it being necessary to lift the stencil and its frame from its bed, as is necessary in machines of this class heretofore in 100 use, and which has been found very objectionable, not only in that it takes time, but also in that the suction between the stencil and the paper, or the solid flat platen upon 105 which the paper rests, tends to draw and crack or tear the stencil.

In operating my device the carriage and its connected parts are first moved forward as shown in Fig. 3; the paper is placed upon the feeding table D'; the paper guides F' G' having been first set to hold the rear end and one side of the paper, which projects over the forward end of the table and slightly over the platen K, as shown in Fig. 3. The carriage is now drawn back, the tappets Y engage the 110 forward end of the cam S and move it back, and the ink roll H falls upon the stencil and the springs M lift the platen up, which forces the paper against the bottom of the stencil. The carriage is now pushed forward, the more 115 rapidly the better, and the ink is forced from the ink roll through the stencil and the characters upon this latter are printed upon the paper during its passage over the platen. Upon the completion of the stroke the paper 120 falls into the receiving box H'.

While I have described my machine as printing only upon its forward stroke, it will be understood that the machine might be adapted to print upon its backward stroke 125 and to remain idle upon its forward stroke. It will also be understood that the machine

can be operated by power if desired instead of by hand.

While I have described my stencil carrying frame as detachably secured to the carriage 5 I do not desire to confine myself to this construction as it, if desired, may form part of the carriage. It will be obvious that any suitable means may be employed for clamping the removable stencil frame to the carriage, 10 and while I prefer to use the means that I have shown for this purpose, still I do not desire to confine myself solely to these means.

Having thus described my invention, I claim as new and desire to secure by Letters 15 Patent—

1. In a stenciling machine, in combination, an inking roll, a platen, a stencil adapted to be reciprocated, and mechanism whereby said inking roll and platen are caused to move at 20 the same speed as that of said stencil.

2. In a stenciling machine, in combination, a stencil adapted to be reciprocated, means for supporting the same, an inking roll adapted to bear against one side of said stencil, a 25 cylindrical platen adapted to hold the paper against the other side of said stencil, and mechanism for positively driving said inking roll and platen, at the same speed as that of said stencil.

3. In a stenciling machine, in combination, an inking roll, a cylindrical platen, and a stencil adapted to be reciprocated, means for supporting said devices, and positive gearing by which said devices are caused to move at a 35 uniform speed.

4. In a stenciling machine, in combination, a stencil adapted to be reciprocated, an inking roll located upon one side of said stencil, a rolling platen located upon the other side 40 of said stencil, and adapted to hold the paper up against the same, means for driving the inking roll and platen, means for bringing the inking roll, in the movement of the stencil in one direction, into contact with the stencil, 45 and means for throwing the inking roll, in the movement of the stencil in the opposite direction, out of contact with the stencil.

5. In a stenciling machine, in combination, a stencil adapted to be reciprocated, an inking roll located upon one side of said stencil, a rolling platen located upon the other side of said stencil and adapted to hold the paper against the same, means for driving the inking roll and platen, means for bringing the inking roll, in the movement of the stencil in one direction, into contact with the stencil and the rolling platen into contact with the paper beneath the stencil, and means for throwing the inking roll and platen, in the 55 movement of the stencil in the opposite direction, out of contact with said stencil and paper respectively.

6. In a stenciling machine, in combination, a stencil adapted to be reciprocated, an inking roll located upon one side of said stencil, a rolling platen located upon the other side of said stencil, and adapted to hold the paper

against the same, mechanism for driving the inking roll and platen at the same speed as that of the stencil, means for bringing the inking roll, in the movement of the stencil in one direction, into contact with the stencil, and means for throwing the inking roll, in the movement of the stencil in the opposite direction, out of contact with said stencil. 75

7. In a stenciling machine, in combination, a stencil adapted to be reciprocated, an inking roll located upon one side of said stencil, a rolling platen located upon the other side of said stencil and adapted to hold the paper up against the same, mechanism for driving the inking roll and platen at the same speed as that of the stencil, means for bringing the inking roll, in the movement of the stencil in one direction, into contact with the stencil 80 and the rolling platen into contact with the paper beneath the stencil, and means for throwing the inking roll and platen, in the movement of the stencil in the opposite direction, out of contact with said stencil and 85 paper respectively.

8. In a stenciling machine, in combination, an inking roll, a platen, and a stencil holder adapted to be moved between said roll and platen, means for automatically throwing the 90 inking roll into and out of contact with the stencil at predetermined points of the travel of the latter, substantially as set forth.

9. In a stenciling machine, in combination, an inking roll, a rolling platen, and a stencil 100 holder adapted to be moved between said roll and platen, and means for automatically throwing the inking roll and rolling platen into and out of contact with the stencil at predetermined points of the travel of the latter, substantially as set forth. 105

10. The combination with a reciprocating carriage and means for supporting and reciprocating the same, a stencil carried by this carriage, a platen and an inking roll, of a rack 110 or racks carried by said carriage, a gear wheel or wheels carried by shaft of said inking roll, and an intermediate gear wheel or wheels gearing into said racks and gear wheels on said inking roll. 115

11. The combination in a stenciling machine of a reciprocating carriage and means for supporting the same, a stencil frame and stencil carried by this carriage, an inking roll, a cylindrical platen, a rack carried by said carriage, a gear on the shaft of said platen engaging said rack, and a gear on the shaft of said inking roll engaging the gear on the shaft of said platen. 120

12. The combination in a stenciling machine 125 of a reciprocating carriage, a bed plate upon which said carriage works, a stencil frame and stencil carried by said carriage an inking roll and cylindrical platen, arms pivoted to said bed plate and upon which the shaft of said roll and platen are carried and means substantially as described for moving said roll and platen into contact with said stencil during the forward or printing movement of the 130

latter, and for moving them out of contact with said stencil during its backward or non-printing movement.

13. The combination with the bed plate, the reciprocating carriage mounted upon the bed plate and the stencil carrying frame and stencil carried by said carriage, of the inking roll and cylindrical platen, arms pivoted to said bed plate and carrying said roll and platen, springs for supporting the arms carrying said platen, guides carried by said bed plate, double faced cams sliding on said guides, tappets carried by said carriage and adapted to move said cams and adjustable contact pieces carried by said arms and engaging the faces of said cams, all substantially as and for the purposes set forth.

14. The combination with the inking roll and platen and the arms which carry this roll and platen of adjustable contact pieces carried by said arms, cams adapted to engage said contact pieces, guides upon which said cams slide, a reciprocating carriage and devices carried by said carriage and adapted to actuate said cams.

15. The combination in a stenciling machine of a reciprocating carriage, means for supporting said carriage, a stencil carried by said carriage, an inking roll and cylindrical platen and means for separating said inking roll and platen from contact with the stencil during the non printing movement of the machine.

16. The combination with the inking roll and the arms which carry it, of a frame attached to or forming part of said arms, two or more ink distributing rolls journaled in bearings in said frame, and two or more ink distributing rolls journaled in bearings in bars adjustably attached to said frames and adapted to engage said lower ink distributing rolls and the main inking roll.

17. The combination with the bed plate, a reciprocating carriage and stencil carried on said bed plate, an inking roll and arms one end of which carries said inking roll and the other ends of which are pivotally attached to said bed plate, of springs one end of which is at-

tached to said arms and the other to said bed plate.

18. The combination with the ink roll, platen and reciprocating stencil of a stenciling machine of an adjustable feeding table, and adjustable paper guides carried by said table.

19. The combination in a stenciling machine of a bed plate a carriage having an open center carried by and adapted to be reciprocated upon said bed plate, a stencil carrying frame and a stencil carried by said carriage, an ink roller adapted to ink the top of said stencil, a platen adapted to hold the paper to be printed against the bottom of said stencil, and mechanism substantially as described for driving said inking roll and said platen at the same speed and in the same direction as said stencil.

20. The combination in a stenciling machine of a bed plate, an open carriage reciprocating thereon, a stencil and frame carried by said carriage, means for clamping said stencil frame to said carriage, an inking roll, an ink mixing roll or rolls in contact with said inking roll, a cylindrical platen, a gear wheel or wheels carried by the shaft of said platen and engaging with a rack or racks carried by said reciprocating carriage, a gear or gears carried by the shaft of said inking roll and engaging with a gear or gears carried by the shaft of said platen, arms pivoted to said bed plate and carrying said inking roll and platen, springs for supporting the arms carrying said platen, adjustable springs connecting the arms carrying said inking roll with the bed plate, guides carried by said bed plate, double faced cams sliding on said guides, adjustable tappets carried by said carriage and adapted to move said cams, adjustable contact pieces carried by said arms and engaging the faces of said cams, an adjustable feeding table, adjustable guides carried thereon, and a box for receiving and holding the paper after it has been printed.
